UNITED STATES PATENT OFFICE.

EDWIN F. REA, OF CHICAGO, ILLINOIS, ASSIGNOR TO F. H. NOBLE & COMPANY, OF CHICAGO, ILLINOIS, A CORPORATION OF ILLINOIS.

MEANS FOR SECURING NAME PLATES AND THE LIKE TO WALLS.

Application filed October 12, 1922. Serial No. 593,945.

To all whom it may concern:

Be it known that I, EDWIN F. REA, a citizen of the United States, residing at Chicago, in the county of Cook and State of Illinois, have invented new and useful Improvements in Means for Securing Name Plates and the like to Walls, of which the following is a specification.

My invention relates to a fastening or attaching appliance which is adapted for use in securing such an article as a name plate fast against the face of an orificed wall, and among various uses is particularly well adapted as a means for fastening the ornamental name plate of an automobile to the front wall of the radiator of the vehicle. The object of my invention is in general the provision of fastening means fitted to serve the requirements of such uses, which shall be economical to manufacture, simple in construction, easy to adjust and apply and if occasion requires to remove, efficient and secure in action, and in a high degree adapted and desirable for the purposes in view. To these ends I have devised and invented the novel fastening device herein-after described, and my invention resides in the new combination and arrangement of fastening members cooperating and organized as described, the essential elements thereof being more particularly pointed out in the appended claims, it being understood nevertheless, that the construction of the parts is susceptible of considerable modification and variation without departure from the spirit of my invention.

In the drawing which accompanies this specification, Figure 1 is a face view of a blank name plate and a portion of a wall illustrating the class of devices to which my invention is applicable; Fig. 2 is a rear view and Fig. 3 a central cross-section on the line 3—3 of Fig. 2 showing the locking pin in locked position; Figs. 4 and 5 correspond respectively to Figs. 2 and 3, but show the locking pin in free or disengaged position; Figs. 6 and 7 show the locking pin detached in two different positions at right angles to each other; and Figs. 8 and 9 are bottom plan views of the device (part of the neck being broken away and the wall being shown in section), respectively showing the locking pin in locked position and in free position.

The same reference characters indicate the same parts in all the figures of the drawing.

The name plate 1, or other device which is to be secured to the wall 2, is provided with a neck extending through such wall, in the present instance the neck being cylindrical and formed as short tubular collar 3 extending through a circular orifice of corresponding size in the wall. This collar is formed with two diametrical orifices which constitute bearings for a locking pin 4 which is made of heavy spring wire and is slightly bowed or curved and at one end provided with a radially extending terminal bend 5. Preferably one or more small lugs are pinched up out of the metal of the pin to serve as stops, two being shown in the present instance, so that the pin may be inserted in the orifices in the collar up to the lugs, which will serve to position the pin centrally of its length. The terminal bend 5 serves both as a stop and an operating member, and stands angularly with respect to a plane passing through the bowed pin itself. The curvature of the pin and distance of the bearings from the face of the wall 2 are such that the pin may be freely inserted, and as it is then rotated in its bearings by means of the bend 5 the free end of the pin and the portion of such pin adjacent the base of the terminal bend will come into yielding spring contact with the wall and slide thereon slightly past a dead center position, and then snap into a spring-locked position in which the operating bend 5 will bring up against the face of the wall, thus preventing further rotation, and the spring tension which the pin then exerts at its opposite points of contact will securely retain the name plate in locked position. The cylindrical shape of the neck member permits the name plate to be rotated so as to set it in proper position on the wall before it is locked in place, though it is obvious that the neck may be non-circular in shape in which case its position with relation to the name plate and the cutting of the orifice must be such as to display the name plate in the desired position. Moreover, while I regard a double pivotal bearing of the pin in the tubular neck as desirable, a single central eye or loop acting in the same manner, may be employed, and I regard such

construction as a mere variation and equivalent of that particularly illustrated and described in detail.

I claim:

- 5. 1. Fastening means for attaching a name plate or the like to an orificed wall comprising a neck member secured to the name plate and extending through the wall, said member being formed with a cross orifice
- 10 10. forming a bearing, and a resilient curved locking pin extending through said bearing and arranged to yieldingly engage the face of the wall when rotated.
- 15 2. Fastening means for attaching a name plate or the like to an orificed wall comprising a neck member secured to the name plate and extending through the wall, said member being formed with a cross orifice forming a bearing, and a resilient curved locking pin extending through said bearing and arranged to yieldingly snap past dead center position into spring-locked position, said pin being provided with a stop preventing rotation past locked position.
- 20 25. 3. Fastening means for attaching a name plate or the like to an orificed wall comprising a neck member secured to the name plate and extending through the wall, said member being formed with a cross orifice forming a bearing, and a resilient curved locking pin extending through said bearing and arranged to yieldingly snap past dead center position into spring-locked position, said pin being formed with an operating bend arranged to bring up against the face of the wall and prevent rotation of the pin past locked position.
- 30 35. 4. Fastening means for attaching a name plate or the like to an orificed wall comprising a neck member secured to the name plate and extending through the wall, said member being formed with a cross orifice form-

ing a bearing, and a resilient curved locking pin extending through said bearing and arranged to yieldingly snap past dead center position into spring-locked position, said pin being formed with a terminal radial operating bend set at an angle to the plane of the pin and arranged to bring up against the face of the wall and prevent rotation of the pin past locked position.

45 5. Fastening means for attaching a name plate or the like to an orificed wall comprising a neck member secured to the name plate and extending through the wall, said member being formed with a cross orifice forming a bearing, and a resilient curved locking pin extending through said bearing and arranged to yieldingly engage the face of the wall when rotated, said pin being provided with a stop lug arranged to position it centrally of its length.

55 6. Fastening means for attaching a name plate or the like to a wall having a circular orifice, said means comprising a cylindrical neck member secured to the name plate and extending through said orifice, said member being diametrically orificed to provide a bearing, and a resilient curved locking pin extending through said bearing and arranged to yieldingly engage the face of the wall when rotated.

65 7. Fastening means for attaching a name plate or the like to a wall having a circular orifice, said means comprising a tubular neck member secured to the name plate and extending through said orifice, said member being diametrically orificed to provide a double bearing, and a resilient curved locking pin extending through said bearing and arranged to yieldingly engage the face of the wall when rotated.

75 80 EDWIN F. REA.
